UNITED STATES PATENT OFFICE.

AUDENRIED WHITTEMORE, OF ST. LOUIS, MISSOURI, ASSIGNOR TO GENERAL ROOFING MANUFACTURING COMPANY, A CORPORATION OF ILLINOIS.

HOLDER FOR SHIPPING WALL-BOARDS.

1,168,986.

Specification of Letters Patent.

Patented Jan. 18, 1916.

Application filed February 1, 1915. Serial No. 5,449.

To all whom it may concern:

Be it known that I, AUDENRIED WHITTEMORE, a citizen of the United States of America, and a resident of the city of St. Louis, in the State of Missouri, have invented certain new and useful Improvements in Holders for Shipping Wall-Boards, of which the following is a full, clear, and exact description, reference being had to the accompanying drawings, forming a part of this specification.

My invention relates to improvements in holders for shipping articles, one of the objects being to produce a neat, durable and inexpensive holder adapted to contain large, flat articles, such as sheets of wall-board or plaster-board.

Another object is to produce a very light holder of this kind constructed to serve as a very efficient means for protecting large sheets of wall-board.

Figure I is a perspective view showing a pile of wall-boards and triangular pockets fitted to the corners of the pile of wall-boards. Fig. II is a detail view of one of the triangular pockets. Fig. III is a perspective view of the holder as it appears when the package is ready for shipment. Fig. IV is an enlarged end elevation of the parts shown in Fig. III. Fig. V is an enlarged section taken approximately on the line V—V, Fig. III.

A designates wall-boards piled one above the other and arranged between upper and lower packing sheets 1 and 2 respectively. The packing sheets 1 and 2 serve as protectors for the top and bottom of the pile of wall-boards and they are substantially equal in length and width to the corresponding measurements of the wall-boards. The corners of the wall-boards are protected by triangular corner pockets 3 which preferably inclose the corners of the pile comprising the packing sheets 1 and 2 as well as the corners of the wall-boards A.

The margins of the package are protected by long narrow marginal packing sheets 4 and 5 folded around the margins of the material to be shipped so as to inclose the inner portions of the corner pockets 3. These marginal sheets 4 and 5 are preferably approximately U-shaped in cross-section, and the sheets 4 at the side margins of the package preferably overlap portions of the sheets

5 at the end margins of the package. The 55 packing elements 1, 2, 3, 4 and 5 are preferably made of heavy paper such as chip-board or pasteboard.

6 designates marginal tie members, passing around the side margins of the package, 60 and 7 designates marginal tie members passing around the end margins of the package. The different elements are also tied together by means of an intermediate tie member 8 parallel with the tie members 6, and intermediate tie members 9 parallel with the tie members 7. The different tie members are preferably made of metallic tape and they are preferably interlaced with each other as shown in Fig. III.

10 designates buckles connecting the ends of the tie members.

It will be noted that the different packing elements are so constructed and arranged that they may be very firmly secured together by the marginal tie members 6 and 7 at the margins of the package.

Wall-boards vary in length and width but are ordinarily of such dimensions as 48"x120", 48"x108", and 32"x120", and it 80 has heretofore been quite difficult to pack these large cumbersome articles for shipment. The corner pockets 3, and the marginal members 4 and 5 of my package, may be used in packing wall-boards of different 85 dimensions, and the light package produced by the combination and arrangement of parts I have shown is well adapted to withstand the rough or careless handling to which shipping packages are subjected.

I claim:

A holder for shipping piled wall-boards comprising upper and lower packing sheets, separable triangular corner pockets into which the corners of the pile and upper and lower packing sheets are inserted, folded marginal side and end packing sheets overlapping the body and ends of the pile and upper and lower packing sheets and the corner pockets and overlapped at the corner 100 pockets, and longitudinal and transverse tie members surrounding the body and edges of the packing sheets and the folds of the marginal side and end packing sheets.

AUDENRIED WHITTEMORE.
In the presence of—

A. B. JACKSON,
RUTH H. EDDINGFIELD.
